UNITED STATES PATENT OFFICE

DIEGO ALAMO-YBARRA, OF GENEVA, SWITZERLAND

ADVERTISING DEVICE

Application filed September 7, 1929, Serial No. 391,020, and in Argentina January 25, 1929.

The subject of the present invention is a cut out and fashioned advertising device, characterized by the feature that it presents the outline (silhouette) and the colours, shades and features in fac-simile of the goods, trade or commercial mark or design of the trade and industry for which the said advertisement is intended, the said advertising device containing objects in current or daily use, such as matches, pins, toothpicks, caramels, etc.

The accompanying drawings, which is given by way of example, illustrates one embodiment of the subject of the present invention.

Figure 1 is an elevation showing the interior of a match case in which the top part has not been folded over the bottom part.

Figure 2 is a cross sectional side view, the parts being folded one over the other.

A sheet of cardboard *a*, which is shaped and cut out in such a way that when the two parts *b* and *c* are folded one over the other it presents the outline (silhouette) and features of a barrel (advertisement to be employed by a cooper or a wine merchant) and can thus form a case, a container, a packing, etc. made of any material by means of any process.

Instead of being folded one over the other, two detached sheets presenting the same features as the parts *b* and *c* may also be superposed upon each other.

Between these two sheets is left a sufficient space to permit a movable support *d*, which is fixed or removable carrying the article of daily use, that is to say, in the accompanying drawings, a certain number of matches *e* which support pivots about its pivot *f*. This support may be provided with projections *g* upon which it will be sufficient to press in order to make the said support pivot.

Instead of the support, one of the parts *b* or *c*, may pivot about the pivot *f* thus disclosing the contents of the case.

What I claim is:—

1. An advertising device comprising a covering member adapted to form a container and having the shape of the article to be advertised, a support pivoted within said

cover and adapted to carry suitable articles in current or daily use, the ends of the support projecting slightly beyond the sides of the cover to form projections so that when a pressure is exerted thereon the support will pivot and move out of the cover to permit of the detaching of an article from the support.

2. An advertising device as claimed in claim 1, wherein the support is channel-shaped and wherein fastening means is provided forming a pivot for the support, and a retaining means for the cover.

In testimony whereof I have signed my name to this specification.

DIEGO ALAMO-YBARRA.
